(57) **CLAIM**

The ornamental design for a combined dog collar and leash, as shown and described.

DESCRIPTION

FIG. 1 is a top, left rear perspective view of a combined dog collar and leash showing my new design;

FIG. 2 is a front elevational view thereof;

FIG. 3 is a left side elevational view thereof;

FIG. 4 is a top plan view thereof;

FIG. 5 is a right side elevational view thereof;

FIG. 6 is a bottom plan view thereof; and,

FIG. 7 is a top, left rear perspective view thereof in an exploded condition.

The broken line showing of a section of the leash is included for the purpose of illustrating a part of the combined dog collar and leash that forms no part of the claimed design.

1 Claim, 5 Drawing Sheets

FIG. 1

FIG. 2

FIG. 4
